UNITED STATES PATENT OFFICE.

GEORGE W. BENDER, OF CHICAGO, ILLINOIS, ASSIGNOR TO MUDGE & COMPANY, OF CHICAGO, ILLINOIS, A CORPORATION OF ILLINOIS.

VENTILATOR.

Application filed September 4, 1920. Serial No. 408,219.

To all whom it may concern:

Be it known that I, GEORGE W. BENDER, a citizen of the United States, residing at Chicago, in the county of Cook and State 5 of Illinois, have invented certain new and useful Improvements in Ventilators, of which the following is a specification.

My invention relates to ventilators suitable for use in railway cars, tram cars, or 10 other vehicles and more particularly to the type of ventilator such as that shown in Patents 1,099,838 and 1,275,211 to George C. Breidert, which induces ventilation by the suction created by the impact of air, due to 15 the motion of the car, on a surface arranged at right angles to the direction of movement of the car.

One of the objects of the invention is to provide an improved ventilator of this type 20 of simple construction and which may be easily and cheaply made.

A further object is to provide certain novel arrangements and constructions for increasing the efficiency of this type of ventilator and rendering its operation more satisfactory under low relative air velocities.

A still further object is to provide certain improved constructions and arrangements in a ventilator of this type for preventing back drafts and the entry of side winds into the ventilator.

The invention is illustrated in certain preferred embodiments in the accompanying 35 drawings in which—

Fig. 1 is a perspective view showing a ventilator embodying the principles of my invention applied to a railway car.

Fig. 2 is a transverse section of the construction shown in Fig. 1 taken on a plane transverse to the car and passing through the center of the ventilator.

Fig. 3 is a sectional elevation taken on the line 3—3 of Fig. 2.

Fig. 4 is a section taken along the line 4—4 of Fig. 2.

Fig. 5 is an enlarged fragmentary section illustrating an improved method of securing the sheet metal together.

Fig. 6 is a transverse sectional view of the ventilator slightly modified to adapt its application to a car having an arch roof.

Fig. 7 is a transverse vertical section of a double ventilator.

Fig. 8 is a plan section taken along the

line 8—8 of Fig. 9 illustrating a form of ventilator in which the passage into the car is vertical.

Fig. 9 is an elevation of the ventilator shown in Fig. 8, and

Fig. 10 is a transverse section of the type of ventilator shown in Figs. 1 and 2 modified to be used in conjunction with a blower.

Like characters of reference indicate like parts in the several figures of the drawing.

Referring to Figs. 1 to 5 inclusive, 10 designates the body of a car having a deck 11, clear-story 12, and roof 13. The clear-story is provided with a suitable opening 14 over which a screen 15, if desired, may be placed. The ventilator 16 is arranged in communication with the opening 14 by means of a suitable base 17 in the form of a conduit having marginal flanges 18 secured to the clear-story of the car.

The ventilator 16 comprises in general a box like structure having an imperforate outer face 19 disposed parallel to the direction of movement of the car and air ramming faces 20 and 21 arranged transversely between the outer face 19 and an inner face 27 which is secured to the outer end of the conduit 17.

The air ramming faces 20 and 21 are preferably curved inwardly on the arc of a circle so as to present concave cylindrical outer surfaces. The top and the bottom of the structure are partially closed by spaced baffle plates 24 and 25 which are held in position transversely of the structure by means of flanges 26. The plates 24 and 25 are provided with deflecting flanges 28 and are inclined outwardly toward the middle of the structure as shown in Fig. 3. These plates are spaced so as to provide air openings 29, 30 and 31 in the upper and lower sides of the ventilator.

A plurality of louvres 32 are arranged at the top of the ventilator parallel to the outer face 19 between the air ramming faces 20 and 21. A corresponding set of louvres 33 are arranged at the bottom of the ventilator, being inclined outwardly as shown more clearly in Fig. 2. The inner face 27 of the structure 16 is provided with an opening 34 which communicates with the conduit 17 and is provided along the sides of the opening 34 with outwardly inclined flanges or deflecting plates 35. The lower one of these flanges is numbered 36 and is directed diag-

onally downwardly as shown in Fig. 2 for a purpose to be hereinafter pointed out. The lower surface of the conduit 17 preferably inclines downwardly and outwardly as shown in Fig. 2.

The sheets of metal forming the ramming faces and the inner and outer faces of the ventilator may be secured together at the corners in any approved manner. I have illustrated in Fig. 5 a form of beaded joint 37 which is suitable and serves in addition to provide flanges 38 adjacent to the curved surface of the air ramming face at each side and assisting in collecting the air impinging thereon and directing it across the exhaust passages 29, 30 and 31.

Operation.—The ventilator operates by inducing evacuation of the air in the car by means of the suction created by the current of air directed over the exhaust openings 29, 30 and 31 by the leading ramming face. I have found that when there is a low relative air velocity the air tends to pass in or to be drawn into the ventilator. To prevent this I have arranged the plates 24 and 25 transversely to the stream of air so as to deflect outwardly any current of air tending to enter the ventilator. To make this action more effective I have provided the plates with vertical flanges 28 which assist in directing the air outwardly. In operation the leading plate, that is the plate which is forward depending upon the direction in which the car is moving, is the plate which functions.

The louvres 32 and 33 prevent back drafts and the entry of side winds into the ventilator, especially when the car is standing still or when the side winds are extremely strong. A side wind, deflected upwardly by the deck or roof of the car toward the lower openings 29, 30 and 31 is deflected outwardly by the inclined louvres 33 and passes out through the upper openings 29, 30 and 31, assisted by the suction of the side wind over the upper side of the ventilator. The lower flange 36 turns such side winds downwardly and also prevents the entry of rain and dust. The upper louvres 32 deflect any side winds, dust or rain entering through the openings at the top downwardly and out through the openings at the bottom.

The principles of my invention are adapted for use in connection with any type of car or vehicle and are not limited to a car having a clear story as shown in Fig. 1.

For the purpose of illustration I have shown in Fig. 6 my ventilator applied to a car having an arch roof. The ventilator is connected to the opening 39 in the car roof by means of an exhaust conduit 40 to which the ventilator is connected by means of the flanges 41. The lower edge of the opening 42 connecting the ventilator and the exhaust conduit is provided with an inclined plate

43 which serves the same function as the inclined bottom of the conduit 17 shown in Fig. 2, namely, to turn outwardly rain and dust which may find entrance into the ventilator. In other respects the ventilator is the same as that described in Figs. 1 to 5 inclusive.

The separate construction of ventilator and conduit enables the application of a standard form of ventilator to different forms of conduit, the conduit being made to conform to the particular car construction.

In Fig. 7 I have shown a construction by means of which it is possible to employ a pair of oppositely disposed ventilators constructed in general like that shown in Fig. 6. The ventilators project from the sides of an exhaust conduit 44 placed over the opening 45 in the top of the car. A baffle plate 46 divides the interior of the exhaust conduit into two passages 47 and 48 leading to the ventilators 49 and 50 respectively. The baffle plate prevents the short circuiting of the air current from one ventilator through the other. In ordinary operation it is seldom that the suction through each of the ventilators 49 and 50 will be the same, owing to the fact that the resultant air current is not always dead ahead. The unbalancing of the suction of the two ventilators tends to draw through one and out the other instead of drawing from the car through the opening 45. The baffle plate 46 prevents this by dividing the conduit into two passages 47 and 48 so that the air exhausted through the ventilators 49 and 50 will be drawn from the interior of the car.

In Figs. 8 and 9 I have illustrated the principles of my invention applied to a vertically arranged air duct. In this type of ventilator the air is drawn upwardly through the vertically arranged cylindrical conduit 51. The air ramming faces 52 and 53 are arranged so as to deflect the impinging air past the sides of 54 and 55 of the ventilator. These sides are open and provided with transverse plates 56 and 57 as more clearly described in connection with Figs. 1 to 5 inclusive. The upper end of the cylindrical conduit 51 is provided with openings 58 which face in a direction at an angle to the exhaust openings 54 and 55 of the ventilator. These openings 58 are provided with outwardly extending deflecting flanges 59 formed preferably by bending outwardly the metal of the conduit which prevent the entry of side winds tending to pass through the central openings 60 into the interior of the conduit 51. The top 61 of the ventilator is imperforate.

In Fig. 10 I have illustrated a ventilator embodying the principles of my invention and modified so as to adapt it to be used in conjunction with an exhaust fan or blower.

Such a construction is of use especially in dining or private cars where the need for ventilation while cars are standing is greater than in other types of cars. The ventilating fan is intended to be used only when the car is standing still and when the ventilator does not function automatically. When the car starts the fan is stopped and the ventilator operates in the same manner as that 5 illustrated in Figs. 1 to 5 inclusive.

The ventilator 62 is of the general box like construction secured to the clear story of the car and communicating with the interior thereof through the opening 62'. The ventilator is provided with transverse plates 63 and 64 and louvres 65 and 66 and deflecting flanges 67 and 68 as in the form of construction illustrated in Figs. 1 to 15 5 inclusive. The opening 62' of the ventilator is connected to any suitable type of exhausting fan or blower 69 by means of a conduit 70.

The outer face 71 of the ventilator opposite the opening 62' is provided with a plurality of horizontal downwardly inclined louvres 72 secured within the rectangular opening formed by the outwardly extending flanges 73.

When the exhaust fan is in operation the 30 air is exhausted directly through the space between the louvres 72 and is not required to pass through the exhaust passages in the upper and lower sides of the ventilator. This prevents the choking of the ventilator 35 when a large quantity of air is attempted to be passed through it.

When the car is in motion, the fan being at rest, the air is exhausted in the usual manner by drawing it from the interior 40 through the blower and out of the upper and lower exhaust openings and also through the outer face 71 by the suction created by the current of air deflected past the face 71 by the leading flange 73.

I claim:

1. A ventilator for cars or the like consisting of a hollow box-like structure comprising a base having an opening therein adapted to communicate with the interior of 50 the car, and an air ramming face disposed transversely to the direction of movement of the car, said box like structure having exhaust passages adjacent said air ramming face, deflectors in said exhaust passages disposed transversely to the current of air deflected by said air ramming face, and means on said deflectors for preventing the entry of the air current into the ventilator.

2. A ventilator for cars or the like consisting of a hollow box-like structure and comprising a base having an opening therein adapted to communicate with the interior of the car, oppositely disposed air ramming faces, means providing exhaust passages 60 between said faces in said box like structure

and spaced deflecting plates in each of said passages disposed transversely to the air current deflected over said passages provided with means for preventing the entry of air into said ventilator between said 70 plates.

3. A ventilator for cars or the like consisting of a hollow box-like structure and comprising a base having an opening therein adapted to communicate with the interior 75 of the car, oppositely disposed air ramming faces, means providing exhaust passages between said faces in said box like structure and spaced oppositely inclined plates in each of said passages disposed transversely to the air current deflected over said passages and having their outer edge portions arranged substantially in the planes passing through the opposite edges of the air-ramming faces.

4. A ventilator for cars or the like, comprising a hollow structure formed with an opening communicating with the interior of the car, and provided with a smooth concave air-ramming face disposed transversely with respect to the direction of movement of 90 the car, and formed with a cylindrical curvature about a single axis, said structure being also provided with an exhaust passage communicating with said opening and terminating in exhaust openings at the curved edges 95 of said air-ramming face, said exhaust openings being provided with plates disposed across the same and inclined outwardly and away from said air-ramming face so as to deflect outwardly the currents of air passing over such exhaust openings.

5. A ventilator for cars or the like comprising a hollow structure formed with an opening communicating with the interior 100 of the car, and provided with an inwardly curved air ramming face disposed transversely to the direction of movement of the car, and with an exhaust passage communicating with said opening and terminating in exhaust openings at opposite edges 105 of said air ramming face, said exhaust openings having a plate disposed therein inclined outwardly and away from said air ramming face and provided with a deflecting 110 flange on the outer edge thereof parallel to said air ramming face.

6. A ventilator for cars or the like comprising a hollow box-like structure adapted to communicate with the interior of the car and provided with air ramming faces disposed transversely to the travel of the car and having exhaust passages opening between opposite edges of said air ramming faces, a pair of spaced air deflecting plates disposed transversely of each of said passages and inclined outwardly toward the middle thereof and louvres disposed longitudinally of said passages and intersecting said plates.

7. The combination of a railway car having

ing an opening in the roof thereof, of a ventilator connected with said opening and comprising a box-like structure having an imperforate plate opposite said opening, air 5 ramming faces disposed transversely to the line of movement of the car and upper and lower open sides between said faces constituting exhaust passages, spaced plates in each of said passages and disposed trans- 10 versely to the air currents across said pas- sages and inclined outwardly toward the middle, and upper and lower sets of louvres in said passages, respectively, disposed transversely with respect to the opening into the car, said lower set of louvres inclining away from said opening.

8. The combination of a railway car having an opening in the roof thereof, of a ventilator connected with said opening and comprising a box-like structure having an imperforate plate opposite said opening, air 20 ramming faces disposed transversely to the line of movement of the car and upper and lower open sides between said faces constituting exhaust passages, spaced plates in each of said passages and disposed trans- 25 versely to the air currents across said pas- sages and inclined outwardly toward the middle, and upper and lower sets of louvres in said passages, respectively, disposed transversely with respect to the opening into the car.

9. The combination of a railway car having an opening in the roof thereof, of a 35 ventilator connected with said opening and comprising a box-like structure having an imperforate plate opposite said opening, air ramming faces disposed transversely to the line of movement of the car and upper and lower open sides between said faces constituting exhaust passages, spaced plates in each of said passages and disposed trans- 40 versely to the air currents across said pas- sages and inclined outwardly toward the middle, and upper and lower sets of louvres in said passages, respectively, disposed transversely with respect to the opening into the car, said lower set of louvres inclining away from said opening, and said upper set 45 of louvres being substantially parallel to said opening.

10. The combination of a railway car having an opening in the roof thereof, of a 55 ventilator connected with said opening and comprising a box-like structure having an imperforate plate opposite said opening, air ramming faces disposed transversely to the line of movement of the car and upper and lower open sides between said faces constituting exhaust passages, spaced plates in each of said passages and disposed trans- 60 versely to the air currents across said pas- sages and inclined outwardly toward the middle, and upper and lower sets of louvres in said passages, respectively, disposed trans-

versely with respect to the opening into the car, and inclined deflecting plates around the edges of said opening.

11. The combination of a railway car having an opening in the roof thereof, of a 70 ventilator connected with said opening and comprising a box-like structure having an imperforate plate opposite said opening, air ramming faces disposed transversely to the line of movement of the car and upper and lower open sides between said faces constituting exhaust passages, spaced plates in each of said passages and disposed trans- 75 versely to the air currents across said pas- sages and inclined outwardly toward the middle, and upper and lower sets of louvres in said passages, respectively, disposed transversely with respect to the opening into the car, said opening having a down- 80 wardly inclined plate extending from the lower edge thereof.

12. In combination with a railway car, a ventilator secured to the exterior of the car so as to project therefrom and connected thereto by a laterally extending exhaust conduit, said ventilator comprising a hollow box-like structure provided with air ramming faces disposed transversely to the movement of the car and having exhaust openings in the upper and lower faces thereof of adjacent the edges of said air ramming faces, spaced plates across each of said openings and disposed transversely to the direction of movement of the car and inclining outwardly toward the middle of said openings, louvres in said openings extending between said air ramming faces, outwardly extending deflecting plates around the edges of the opening of said exhaust conduit into said ventilator, the bottom of said conduit being inclined downwardly and outwardly.

13. In combination with a railway car, a ventilator secured to the exterior of the car so as to project therefrom and connected thereto by a laterally extending exhaust conduit, said ventilator comprising a hollow box-like structure provided with air ramming faces disposed transversely to the movement of the car and having exhaust 110 openings in the upper and lower faces thereof of adjacent the edges of said air ramming faces, spaced plates across each of said openings and disposed transversely to the direction of movement of the car and inclined outwardly toward the middle of said openings, louvres in said openings extending between said air ramming faces, outwardly extending deflecting plates around the edges of the opening of said exhaust conduit into said ventilator, and a downwardly and out- 115 wardly inclined plate in the lower edge of the opening of said ventilator into said conduit.

14. The combination in a railway car or the like having an opening in the wall 130

thereof, of an exhaust conduit connected with said opening and projecting from the car wall and terminating in a flanged opening, a box-like ventilator provided with 5 air ramming faces arranged transversely to the movement of the car, and having exhaust openings therein adjacent said air ramming faces, and having a flanged opening in the side adjacent said conduit and depending 10 tachably connected thereto by means of said flanges, the opening in said conduit conforming to the size of the flanged opening in said ventilator.

15. A ventilator for cars or the like con-

sisting of a hollow box-like structure and comprising a base having an opening therein adapted to communicate with the interior of the car, oppositely disposed air ramming faces, means providing exhaust passages between said faces in said box like structure 20 and a pair of spaced plates across each of said passages and inclining outwardly toward the center of said passages respectively and disposed transversely to the direction of movement of the car, said plates having 25 deflecting flanges on their outer edges parallel to their ramming faces.

GEORGE W. BENDER.
